UNITED STATES PATENT OFFICE.

JOHN F. BYRNE, OF KALAMAZOO, MICHIGAN.

CONTAINER.

Application filed October 26, 1927. Serial No. 228,874.

The main object of this invention is to provide a container of the type having sealed end closing flaps with means facilitating the opening to afford access to the contents or removal thereof and effective reclosing.

A further object is to provide a container having closure means of this character which does not add materially to the cost of the container and is at the same time very convenient to manipulate.

Objects relating to details and economies of my invention will appear from the detailed description to follow. The invention is defined and pointed out in the claims.

15 A structure which is a preferred embodiment of my invention is illustrated in the accompanying drawing, forming a part of this specification, in which:

Fig. 1 is a perspective view of a container embodying the features of my invention.

Fig. 2 is a plan view of the blank from which the container shown in Fig. 1 is formed.

25 Fig. 3 is a fragmentary top perspective view showing further details of the container when sealed.

Fig. 4 is a top perspective view corresponding to that of Fig. 3 after the container has been opened and reclosed.

Fig. 5 is a transverse detail section on a line corresponding to line 5-5 of Fig. 4.

Fig. 6 is a fragmentary perspective view with the container opened.

35 Fig. 7 is a detail section on a line corresponding to line 7-7 of Fig. 4.

In the drawing similar numerals of reference refer to similar parts throughout the several views.

40 Referring to the drawing, my improved box or container is preferably formed of an integral blank as shown in Fig. 2, the blank consisting of side wall portions 1, 2, 3 and 4, the side wall having a sealing flap 5 at its outer edge. These side wall portions have bottom flaps 6, 7, 8 and 9 which are folded and sealed together in the usual manner.

45 The top of the container is provided with closing flaps 10, 11, 12 and 13, the flaps 11 and 13 being the inner flaps and when closed their edges lie in spaced relation. The flaps 10 and 12 overlie the flaps 11 and 13, the overlapping portions of the flaps 10 and 12 being sealed together by means of a suitable adhesive.

55 The flaps 10 and 12 have aligned severing

scores or perforations 14 and 15, the flap 10 also having a cross slit 16 extending between its severing perforations 14.

The outermost flap 12 has a curved slit 17 disposed centrally between its transverse severing perforations 15, the slit 17 forming a tongue-like member 18 with which a finger-nail or an implement may be engaged to facilitate opening the container.

60 At the ends of the slit 17 are severing perforations 19, these perforations extending to the transverse severing perforations 15.

65 The outermost flap 12 is also provided with tongue-forming slits 20 which form laterally projecting tongues 21 which extend beyond the transverse severing perforations or scores 14 of the underlying flap 10.

70 The slits 16 and 17 are formed at the overlapping portions of the flaps 10 and 12 and are spaced so that when the container is opened, a pair of oppositely swinging closure members 22 and 23 are provided, the ends of the closure members overlapping.

75 In opening the container, the finger nail or an implement is engaged in the slit 17 and pulled upwardly which ruptures the container along the severing lines described, thereby opening the container and forming two closure members. To reclose the car-
80 ton, the member 22 is first swung downwardly, the member 23 then swung to closed position with its end overlapping the end 22, and the tongues 20 are snapped under the edges of the closure members thereby re-
85 taining the closure members.

90 My improved container is very convenient to manipulate in opening and reclosing.

I have illustrated and described my improvements in a satisfactory embodiment. 95 I have not attempted to illustrate adaptations to other forms of containers as it is believed this disclosure will enable those skilled in the art to embody or adapt my improvements as may be desired.

100 Having thus described my invention, what I claim as new and desire to secure by Letters Patent, is:

1. A container, the end of which is closed by spaced inner flaps and overlapping outer flaps sealed together, said overlapping flaps having transverse spaced and aligned severing perforations, the outer of said overlapping flaps having tongue forming slits there-
105 in merging with its said transverse severing perforations and providing lateral tongues projecting beyond the transverse severing

- perforations of the inner of said overlapping flaps, the inner of said overlapping flaps having a cross slit between its said transverse severing perforations, the outer of said overlapping flaps having a curved cross slit connected to its said transverse severing perforations by severing perforations, said curved slit providing a hold member facilitating the rupturing of the flaps along said severing perforations providing a pair of closure members having overlapping end portions, one of which has laterally projecting tongues engageable with the edges of the closure opening for retaining the closure members in closed position after the container has been initially opened.
2. A container, the end of which is closed by spaced inner flaps and overlapping outer flaps sealed together, said overlapping flaps having transverse spaced and aligned severing perforations, the inner of said overlapping flaps having a cross slit between its said transverse severing perforations, the outer of said overlapping flaps having a curved cross slit connected to its said transverse severing perforations by severing perforations, said curved slit providing a hold member facilitating the rupturing of the flaps along said severing perforations providing a pair of closure members having overlapping end portions.
3. A container having overlapping closing flaps sealed together, said overlapping flaps having transverse spaced and aligned severing perforations, the outer flap having tongue forming slits therein merging with its said transverse severing perforations and providing lateral tongues projecting beyond the transverse severing perforations of the inner flap, the inner flap having a cross slit between its said transverse severing perforations, the outer flap having a cross slit and severing perforations extending from the ends of said slit to its said transverse severing perforations, said slit in said outer flap providing a hold facilitating the rupturing of the flaps along the said severing perforations providing a pair of closure members having overlapping end portions, one of which has laterally projecting tongues engageable with the edges of the closure opening for retaining the closure members in closed position after the container has been initially opened.
4. A container having overlapping closing flaps sealed together, said overlapping flaps having transverse spaced and aligned severing perforations, the inner flap having a cross slit between its said transverse severing perforations, the outer flap having a cross slit and severing perforations extending from the ends of said slit to its said transverse severing perforations, said slit in said outer flap providing a hold facilitating the rupturing of the flaps along the said severing perforations providing a pair of closure members having overlapping end portions.
5. A container having overlapping closing flaps sealed together, said flaps having transverse spaced aligned severing perforations, the inner flaps having a cross slit between its said transverse severing perforations and the outer flap having a cross slit to facilitate grasping, and severing perforations from the ends of such slit to said transverse perforations, said cross slits being arranged in spaced relation in the overlapping parts of the flaps so that when the flaps are ruptured along said severing perforations, a pair of closure members having overlapping ends are provided, the longer of said closure members having laterally projecting retaining tongues engageable with the edges of the closure opening.
6. A container having overlapping closing flaps sealed together, said flaps having transverse spaced aligned severing perforations, the inner flaps having a cross slit between its said transverse severing perforations and the outer flap having a cross slit to facilitate grasping, and severing perforations from the ends of such slit to said transverse perforations, said cross slits being arranged in spaced relation in the overlapping parts of the flaps so that when the flaps are ruptured along said severing perforations, a pair of closure members having overlapping ends is provided.
7. A container having overlapping closing flaps sealed together, said flaps having spaced transversely aligned severing scores extending across the container, said flaps also having in their overlapping portions cross severing scores positioned between said transverse severing scores and spaced to provide coengaging closure parts so that when the flaps are ruptured along said cross and transverse severing scores, a pair of closing members having overlapping ends is provided, the longer of said closure members having a retaining tongue engageable with an edge of the closure opening.
8. A container having overlapping closing flaps sealed together, said flaps having spaced transversely aligned severing scores extending across the container, said flaps also having in their overlapping portions cross severing scores positioned between said transverse severing scores and spaced to provide coengaging closure parts so that when the flaps are ruptured along said cross and transverse severing scores, a pair of closing members having overlapping ends is provided.

In witness whereof I have hereunto set my hand.

JOHN F. BYRNE.
